UNITED STATES PATENT OFFICE.

ROBERT W. SCOTT, OF BABYLON, NEW YORK, ASSIGNOR TO SCOTT AND WILLIAMS, INC., OF NEW YORK, N. Y., A CORPORATION OF MASSACHUSETTS.

RIBBED-FABRIC-HOSIERY-KNITTING MACHINE.

Application filed May 9, 1922. Serial No. 559,506.

This invention relates to knitting machines adapted to knit ribbed fabric or plain fabric, or articles of hosiery containing both ribbed-fabric and plain-fabric parts side by side, or end to end, or both; as, for example, to knit by continuous circulatory or oscillatory operations a seamless stocking having a ribbed leg with a welt, and portions, for example the instep and sole, of conjoined ribbed and plain fabric.

One object of the invention is to provide a machine having all of the customary plain-fabric stocking-knitting appliances, such as usually employed in knitting the leg, heel, foot and toe portions of a stocking, with devices also capable of knitting a segment of the tube, or all of the tube, of ribbed fabric, and adapted, by the automatic operation of the machine, to knit an article of hosiery having portions all of plain fabric, or partly of rib and partly of plain fabric or all of plain fabric; or successively of each of these fabrics; and capable of making loose courses and tubular welts at places in the fabric, and of knitting separately by a continuous operation a succession of articles containing as features portions of the respective fabrics, or any of them, each article being complete, in the case of stockings, except for the closure of the toe-seam, and certain optional treatments of the welt.

Other objects of the invention are to provide for the improved manufacture of ribbed-leg and ribbed-instep stockings, to provide means for the improved passage from plain to ribbed fabric, for the improved formation of tubular welts at the end of a stocking knit from toe to top, and to produce improved partly-ribbed and partly-plain articles of hosiery without resorting to transfer of loops from one needle to another. Still further objects of the invention are to provide improved means for selvaging and for tucking, to provide improved means for maintaining upon the fabric formed by the machine and in respect to the instruments used a sufficient tension for the most effective operation; to provide means for severally operating different segments of the knitting and tensioning instruments at different times; and to provide by changes of stitch-length, of yarn and otherwise for the production of stockings having well-shaped parts of appropriate texture.

A general object of the invention is to combine devices for automatic coordination for the above purposes, and within the severe conditions set by limitations of space and necessity for non-interference between the several agencies of a machine of the automatic circular stocking-knitting type, so that the new devices shall still be capable of correct, reliable and automatic performance of all of the old as well as of the new functions reaching the objects above mentioned, and thus be adapted to turn out products of uniform excellence with a minimum of attention by the operator.

The invention utilizes some of the instruments of my prior application Serial No. 461,195, filed April 14, 1921, for rib-knitting by the operation of a complementary pair of series of knitting instruments; provides means for actuating these parts in a different way for the present purposes, and provides a web-holder mechanism adapted to cooperate differently with respective segments of the needles and fabric being made for the purpose of aiding the knitting and cast-off functions, replacing the fabric take-up usual in rib-knitting machines, and adapted for the purpose of knitting in separate succession partly ribbed and partly plain hosiery according to the present disclosure. I do not herein claim the invention common to my said application and this disclosure.

These devices are combined with means adapted to the new devices for automatically adjusting the machine to accommodate its new and old agencies to the successive different parts of its product, as these are produced.

The invention will now be explained in connection with a specific embodiment arranged to knit ribbed-instep and ribbed-leg stockings from toe to top and shown in the accompanying drawings, in which—

Fig. 1 is a right side elevation of the machine, parts being in section; 100

Fig. 5 is a development of the cylinder cams showing paths taken by certain of the needles;

Fig. 6 is a plan in section through the dial cams showing the preferred relation of the dial cams to the cylinder cams by comparison with Fig. 5;

Fig. 7 is a detail plan partly in section on the line 7—7 of Fig. 2 showing the dial cap 10 and operating connections, the latch ring, the yarn feeding fingers and the yarn severing and clamping means;

Fig. 8 is an enlarged exterior development of a part of the dial verge, the fabric 15 tensioning fins or ribs on the dial, the cylinder and dial needles, and the web holders;

Fig. 9 and Fig. 10 are respectively enlarged elevations of plain web holders and of tensioning web holders;

Fig. 11 is an enlarged detail of Fig. 2 in section illustrating a preferred construction at the verge of the dial;

Fig. 12 is a plan above the bed plate and cylinder cams, showing the needle pickers, 25 the switch and dividing cams, the auxiliary needle raising and depressing cams, and the operating connections for these parts;

Fig. 13 is an enlarged elevation partly in section on line 13—13 of Fig. 12, showing 30 means for operating the bottom center cam;

Fig. 14 is a rear side elevation; Fig. 15 a plan; and Fig. 16 an under plan of the web-holder cam cap;

Figs. 17, 18 and 19 are respectively sections on the lines 17—17, 18—18 and 19—19 of Fig. 15;

Fig. 20 is a detail right side elevation on a reduced scale of the connections for raising and lowering the dial and for working 40 one of the web holder cams;

Fig. 21 is a comparative diagram illustrating the relations to each other of parts of the means for raising and lowering the dial and parts of the mechanism for operating 45 the dial cams;

Fig. 22 is a diagram plan showing the relations of the different kinds of operating butts of the knitting and fabric-tensioning instruments;

Fig. 23 is a diagram elevation of a portion of the instruments of the machine and of the fabric illustrating the relations of the different instruments to the fabric;

Fig. 24 is a diagram elevation of a stocking 55 illustrating one typical product;

Fig. 25 is a detail showing the stocking foot as delivered by the machine, before looping;

Fig. 26 is an enlarged longitudinal section 60 through the top of the leg and the welt of the stocking shown in Fig. 24; and

Fig. 27 is an enlarged outside or face view diagram of the fabric at the junctures of plain and ribbed knitting, for instance at 65 the areas 27^a and 27^b of Fig. 24.

The advantages in general of the machine of this invention will best be understood by reference to one product capable of manufacture on it. Stockings for winter or sporting wear, or for children, are most satisfactory when made of ribbed fabric, which combines elastic properties insuring comfort and a good fit with an excellent appearance.

Referring now to Figs. 24 to 27, these illustrate a preferred product and certain steps in the art or method of producing it, not herein claimed, for explanation of the results and advantages of this machine. As shown, the stocking *l*, Fig. 24, comprises a 75 seamless foot having the usual plain fabric toe *t*, a plain fabric ring *t'* next to the toe; a plain fabric sole *S* and ribbed instep *p*, (which may have any desired number of 80 wales proportionally to the total number of wales anywhere in the product); the usual heel *h*, and a short section of plain fabric *h'* above the heel.

The leg *L* is of rib knitting, preferably of uniform pattern such as 2-and-1 or 4-and-1, 90 and at the junctures *r*¹ and *r*² between ribbed and plain a sharp line of demarcation free from holes, of strong fabric and of attractive appearance, is secured by a structure presently explained. The leg is preferably 95 fashioned at the calf by predetermined variation in the length of stitch, and the upper end of the stocking is provided with a welt *W* of plain fabric of desired length, ending in a section *W'* of ribbed fabric, 100 Fig. 26, which may, if desired, be sewed to insure durability on the line *w*²—*w*², *w*²—*w*³, or both.

In some cases, where a turned welt of ribbed fabric only is desired, the plain-fabric welt *W* made by the automatic operation of the machine may be very short to serve only as a guide for use in applying the inturned upper end of the leg *L*, at the predetermined length fixed by the machine-placed welt, to the pins of a looper, in order to sew down a portion of the inturned upper end of the ribbed leg to form the welt. When this is done, the machine-made welt *W* may be raveled away or cut off after 115 sewing. Whichever way of finishing the fabric is resorted to, the machine automatically predetermines the length, the stitch-length, the kind of yarn, and all other features of the structure made.

Referring now to Fig. 25, in the preferred operation the stocking is begun by first forming a selvage *s* on the bare needles, for instance by the method explained in my re-issued Patent No. 13,752, June 16, 1914, and by then making looper's rounds *r* of plain fabric before beginning the toe.

The ribbed fabric beginning respectively at the structures *r*¹ and *r*² includes added wales *x*¹, *x*², *x*³ etc. Fig. 27, which may be 130

produced by causing dial needles *a* *b* to enter the spaces between any desired recurrent pairs of cylinder needles *n*. To make the structures *r*¹ and *r*² this entrance is in 5 respect to and to take loops *z* in courses *r*⁵, *r*⁹, into which the loops of tucked (accumulated-loop) partial courses *r*³, *r*⁴ are detained to be cast off with the knit loops *r*⁷ of the courses *r*⁵, *r*⁹. The tucked loops are 10 independent in number, in the parts of the course containing them, of the number of rib wales *x*¹ etc., but preferably are in such number as to occur always in one or the other of the wales flanking that containing 15 an initial dial loop *z*. The leg of a loop *r*⁷ thus always extends across the eyelet-hole which would otherwise be formed.

For forming the selvage *s*, alternate needles of one of the two series, cylinder 20 and dial, are arranged to be active and inactive, the remainder being ever-active. The tuck stitches in the demarking structures *r*¹ and *r*² are formed on these occasionally active needles.

25 *The machine generally.*—Referring to Figs. 1, 2 and 5, the machine frame parts B, etc., the drive-shaft 32, and geared connections 30, 31 and *g*, *g*⁵, 33, *g*⁴, *g*³, *g*⁶, *g*², *g*¹, respectively for driving in unison the cylinder 260, the dial-spindle *d* and dial D concentric with the cylinder and rotatable in a bearing *d*⁸ of bracket A on the latch-guard ring 550, may all be substantially like the prior machines. The ring 550, dial D, and 30 their attachments are pivoted at 552, and may be lifted away from relation to the other parts, all, for example, as shown in my prior Patent No. 1,282,958, dated October 20, 1918.

40 The means for operating the shaft 32, the pattern-drum 120 and its driving connections 121, 122, 123; the cam-shaft 80 and its attachments, the primary pattern chain C, Fig. 1, and the thrust-bars 460 serving 45 as operating connections to parts controlled by drum 120 may be substantially those of the prior art.

The needles of the cylinder 260 may be 50 divided into a longer-butts segment (which may include certain medium-butts needles presently mentioned) for the instep, and a short-butts segment for the heel and toe, and for heel and toe knitting may cooperate with automatic yarn-changing means F¹, with the 55 switch-cam 415, the narrowing pickers 650 and widening picker 680, the cam-ring 271, and the knitting cams 357, 360, 361, Fig. 5, in the known way, to knit hosiery articles with narrowed and widened heels and toes. 60 The cylinder needles may be any desired type of needles, shown as latch needles *n*, Fig. 4, having long butts *n*¹, short butts *n*², and medium butts *n*³. Recurrent needles among these, shown as alternate needles, are 65 ever-active needles, and are provided with

jacks 380 actuated by a cam 366, adapted to lift them out of a depression 40, beneath the normal level 41, at which their latches are not cleared of the previous loop, to a level high enough to reach an advancing cam to 70 cause them to clear their latches. The upper surfaces of the respective stitch-cams 360, 361, lift and clear the latches of all needles reaching them.

The drum 120 is moved intermittently, at 75 times by steps corresponding to successive passages by certain points of the cam-ring of the long-butts or the short-butts segments of needles, as in my prior patented machines, and at these points respectively operating 80 cams 4, 25 are movable (by appropriate connections, presently mentioned, to cams on said drum) toward and from the needle-cylinder in stages, to permit their partial insertion during passage of the short-butts, 85 to first operate the leading long-butts needles, and to permit complete insertion before passage of the short-butts. Their withdrawal is in similar stages, to last operate the following end of the long butt segment. The 90 dividing cam 4, Fig. 5, is operated in conjunction with a movable bottom center cam 9 for the purpose of determining whether the needles without jacks shall pass above cam 360 and be active, or shall idly pass 95 beneath the leading and following stitch cams; or shall pass under the leading cam 361 and be elevated by cam 9 to take yarn at times and for purposes again referred to below. Needles with jacks 380 are ever- 100 active and always pass the cams 360, 361 in operative relation, except those with the long and medium butts, which pass above the switch cam 415 and top center cam 357 during reciprocatory knitting, as usual. 105

Other needle cams presently mentioned are operated from the continually but intermittently advanced primary chain C, which initiates motion of shaft 80 and drum 120. The times of all operations are thus related 110 to motions of chain C; of drum 120; of shaft 80, or their attachments, as induced by the primary pattern chain C.

The needle cylinder is vertically movable 115 in respect to the dial D, the latch-ring 550 and cam-ring 271 for the purpose of altering the relation of the cylinder and dial, and also for altering the relation of the limits of the vertical stroke of the cylinder needles to the knocking-over line at the verge of the cylinder. This line is determined by an upper surface of web-holders, presently mentioned, working between the needles, and bearing on an attachment of the cylinder. 120 The effect of lowering the cylinder is to lower the web-holders and relatively to raise the top and bottom limits of the motion of the needles in respect to the web-holders. Means for automatically raising and lowering 125 the cylinder preferably comprise a lever 130

pivoted on the frame stud 450, and having arms 281 and 286 respectively contacting with cams on drum 120 and with a lug on a tube 280, upon which the bottom bearing for cylinder 260 rests, all as well known.

5 Motion of the needle cylinder vertically is made use of in connection with changeable positions of the dial, for purposes explained below, as well as for the usual purposes.

10 *The needle dial.*—The dial D, see Figs. 2, 8 and 11, is rigidly attached to the dial spindle d, is radially grooved at d³ for its knitting instruments, and is peripherally grooved at d¹ to define a narrow circular 15 verge d² an appropriate short distance concentrically within the space defined by the backs of the cylinder needles n. The bottom surface of the dial slopes upwardly at d⁴ to define the narrow verge d². There may be in the dial as many grooves d³ as there 20 are cylinder needles n, or any divisor of this number. The relative rotative positions of cylinder and dial are such as to bring the dial grooves d³ into the radial 25 planes between the grooves for the cylinder needles. The under side of the dial is grooved to leave integral partitions or fins d⁵ in the radial planes of the cylinder needles, preferably all the cylinder needles, as shown 30 in Fig. 8. As shown, there are half as many dial needles as there are alternate ever-active cylinder needles (those provided with jacks), and the rib-pattern is four-and-one. If the intervening empty dial grooves d³ 35 were provided with needles, the pattern would be two-and-one. The needle-dial, the needles, their operating cam-cap and yarn severing and guiding means carried by the cam-cap are provided with raising and lowering means automatically operating to adjust the position of the dial at times, as 40 presently to be mentioned.

The pattern of rib, whether the same all around the stocking or different in different 45 segments, is controlled by the position and relative number of the dial needles, which may be varied within any arrangement permitted by the number of grooves in the dial.

50 As explained below, the dial needles are arranged to be automatically operated in such a way as to be held idle, to make knitting movements, to retire and hold loops, or to be retired empty and remain retired; these operations are effected so as to involve 55 either a selected series, a segment or segments only of the dial needles, for making ribbed-fabric and plain-fabric segments side by side; or to involve all of the dial needles, and thus to make ribbed fabric all around 60 the tube being knit; or to make plain fabric all around the circle on the cylinder needles only, the dial needles then being idle and disengaged from the fabric, or to retire while engaging a loop or bight of yarn, 65 during operation of the cylinder, to make

a welt. The dial needles, (Figs. 3 and 22) shown and preferred are two-part needles, the parts a, b, severally having longer butts a' and b', or shorter butts a² and b², and having hooks facing each other, and arranged and adapted to operate according to my Patent No. 1,385,929, dated July 26, 1921.

70 The cylinder needles, referring now to Figs. 5 and 6, are the primary needles, being fed with yarn prior to passing the radial plane y³, y⁴, of said figures, and knitting at the lower apex of cam 361. The dial needles when active secondarily receive yarn from the cylinder needles, and knit at the radial plane y—y of said figures after the cylinder stitch has been cast off.

75 *The web-holders.*—The cylinder is provided with a web-holder bed 295 and web-holders of two kinds, w¹ and w² Figs. 9 and 10, one web-holder working or lying in a radial plane between every pair of the needles n (Fig. 8) and directly under such dial needles as may be placed in the grooves d³. In planes between the places of the respective adjacent web-holders, and preferably in the radial planes of the cylinder needles, the under surface of the dial is provided with downwardly projecting fins or partitions d⁶, Figs. 2, 8 and 11, which may be integral thin pieces of metal left between radial grooves d⁶ milled in the lower face of the dial, and each having a beveled outer face and smooth lower edges. These fins thus lie between the positions of the web-holders w¹ and w², Figs. 2, 8 and 11.

80 Some of the web-holders are plain web-holders such as shown at w¹, Fig. 9, having upper arms recessed at w³, below the level w¹¹ of the throats under the hooks w¹⁰ which 85 prevent rise of the fabric with the needles. Otherwise the web-holders w¹ are of any desired type, but preferably are each provided with an upper arm w⁵, a parallel lower arm w⁶ having a straight bottom w⁷, and 90 have uniform short and broad operating butts w⁸, and a notch w⁹ for a spring band w¹⁰, Fig. 2.

95 The function of the web-holders w¹ is that usual in the art, the fabric being held down by the hooks w¹⁰ against rising with the needle and the knocking-over line being established in respect to the level w¹¹ of a web-holder slightly withdrawn in respect to the downgoing needle. The web-holders w¹ are 100 placed recurrently among the other web-holders w² as frequently as necessary to provide a web-holder w¹ between each face wale of the fabric, except between those face-wales flanking the position of a rib-wale. 105 At these places a web-holder w² is placed.

110 The web-holders w² are tensioning web-holders, which have the arms w⁵, w⁶, the hold-down hooks w¹⁰, the upper surface w¹¹, 115 and the band notches w⁹, and are in at least 120

two series having respectively different operating means, for instance, short operating butts w^{17} and long operating butts w^{18} , which series may correspond to differentiated segments of the dial-needles which are to be operated independently. The inward end of the arm w^5 is roughened, serrated or provided with forwardly and upwardly projecting points w^{13} , preferably extending above the surface w^{11} and arranged in rounding relation about the end of the upper arm w^5 , and adapted on the forward stroke of the web-holder from an abnormally retracted position, under certain circumstances, to engage the face surface of a back or rib wale and feed forward the fabric extending from the region of the surface w^{11} within and over the end of the arm w^5 , and to release the fabric on the rearward stroke. That is to say, this action takes place when the fabric is properly presented to the tensioning web-holders w^2 . This occurs when the dial is low or the cylinder is high, so that the partitions or fins d^5 on the dial then serve to force the fabric downward over each of the web-holders w^2 and into certain engagement with its fabric-feeding serrations w^{13} . Figure 2 shows the dial at the preferred position for tensioning the fabric by the action of web-holders w^2 . During the making of plain fabric, during welting, and during reciprocating knitting for heels and toes, the dial may be in a relatively high position, and during such times the tensioning web-holders w^2 have normal motions only, and perform the usual functions only in relation to the fabric knit on the adjacent cylinder needles. The web holders w^2 having the longer butts w^{18} may be placed in the instep segment of the needle circle, to correspond to the series of dial needles having the longer butts a^1, b^1 , Fig. 22, for the particular uses of the machine shown.

During the formation of fabric ribbed in one segment and plain in another segment, the tensioning web-holders w^2 may operate as normal web-holders in the plain fabric segment, and be given their tensioning movement in the ribbed-fabric segment, the preferred arrangement for this purpose comprising means for acting differently on the different series of these tensioning web-holders. When the dial is lowered, and the web-holders w^2 have a normal short movement, the serrations w^{13} will engage the back or dial needle-wales of the rib fabric, or the corresponding sinker wales of plain fabric, and feed it inward and downward as it grows, but without exerting any more marked tension than that customary for the web-holders used with cylinder needles for plain-fabric knitting. But upon withdrawing abnormally any of the web-holders w^2 and again advancing them to their normal

inward position, they will exert a full tensioning effect upon the fabric engaged by their serrated ends.

Inward throw of the tensioning web holders w^2 is preferably the function of a single spring-pressed cam adjustable to vary the maximum tension and acting equally upon all of the butts of the tensioning web-holders w^2 .

For the purpose of knitting at will plain tubular fabric, fabric ribbed all around, and ribbed-fabric and plain-fabric segments of the same tubular fabric side by side, this invention provides means by which the normal web-holder function in respect to the plain fabric can be maintained and provides for a proper and different tension in the ribbed fabric whatever its segmental extent to insure the correct operation of the needles to form the ribbed fabric. The machine shown is therefore arranged to operate the described tensioning web-holders in segments corresponding to and variable with the number of active dial needles at any time; for example, to maintain rib-knitting tension on the instep segment, a normal web-holder action on the sole segment, and to provide rib-knitting tension all around the tube during knitting of the ankle and leg. The preferred way of doing this is to control the withdrawing motion of the tensioning web-holders conformably to the number and place of the active dial needles at any time.

By confining the fabric tensioning means to instruments associated with the needles, severally and automatically controlled, I am able to form partly ribbed and partly plain fabric without any of the disadvantages of placing the whole knit web under lengthwise tension; and I am also able to vary the tension on one part of the web, as compared with another part simultaneously being knit, I thus provide for knitting every part of articles produced in separate succession under the best conditions for accurate operation of the knitting instruments proper; strains on the yarn are avoided; and suitable tension is secured for knocking over or completing both the ribbed and the plain fabric stitches during wide variation of the stitch-length for fashioning the stocking or other article.

The web-holder actuating devices.—Referring now to Figs. 1, 2, 9, 10 and 14 to 19 inclusive, the usual grooved web-holder bed 295 fast on the needle cylinder 260 has a running bearing within a depending flange of the web-holder cam cap 300, which is restrained against rotation with the cylinder in each direction by the usual stops 302, Fig. 1, and is further provided (Figs. 14 to 19) with a relatively shallow concentric groove 301 wide enough to take over the broad butts w^8 of the plain web-holders w^2 , and to permit radial play of these web-hold-

ers inwardly to a point sufficient to maintain the hooks w^{10} against the yarn of the last course knit. The band w^{60} holds the web-holders in this position with sufficient tension to prevent centrifugal outthrow of the web-holders. At a segment of the cap 300 wide enough to include the down-going or knitting phase of the motion of the cylinder needles at cams 360 or 361, the groove 301 is widened outwardly at 303, and opposite this widened place a fixed outthrow cam 304, preferably hardened, and stepped at 305 on its upper face, is suitably fastened. The plain web-holders w' at the end of their withdrawal by cam 304 are positively driven inward by relatively thin adjustably fixed cams 306, 307, mounted in horizontal slots 308, 309 cut through the cam cap, and acting on the butt ends of the web-holders w^1 . Cam 307 is active in the direction of round-and-round knitting, and inserts the web-holders moved by it immediately after the recession of the cylinder needles to their lowest point at cam 361, Fig. 5, for the usual web-holder function.

The tensioning web-holders w^2 are independently controlled. Having butts w^{17} , w^{18} respectively higher and narrower than the butts w^8 of the web-holders w^1 , the cap 300 may be provided with any desired system of grooves and cams at a higher level than the cams for the butts w^8 for differently directing the butts w^{17} , w^{18} within the radial limits of the groove 301 or its enlargements. As shown, the cap is provided with a groove 310 deeper and narrower than the groove 301 to accommodate the butts of the tensioning web-holders. This groove has a minimum radius preferably the same as that of the groove 301, and the inward faces of the web-holder butts are all the same radial distance from their hooks w^{10} , so that the inward limit of throw of both kinds of web-holders is the same. But the length of the tensioning web-holders w^2 from their hooks w^{10} to their outer ends is less than that of the plain web-holders, and the tensioning web-holders are thus capable of being withdrawn outwardly without contact with the cams for the plain web-holders to an abnormal distance, for the purpose of seizing by the points w^{18} fabric in position to be so seized. Reinsertion of an abnormally withdrawn web-holder w^2 now tensions the fabric between the points w^{18} and the needles.

All of the tensioning web-holders may be reinserted in common when normally or abnormally withdrawn by a movable cam held inwardly against an adjustable stop by a predetermined spring pressure. As shown, such a cam 312 is pivoted at 313 in slot 309 at a level above the cam 307 and acted upon by an adjustable spring plunger 315 to hold an adjustable eccentric limit stop 314 on

the cam against the wall of the cam-cap. When the function and movement of the web-holders is normal, for plain fabric, the operation of cam 312 is merely to advance these web-holders to their normal inward limit, and provision for positively withdrawing this cam when its special function is not called for is therefore avoided.

When knitting reciprocally it is desirable to operate the tensioning web-holders on the back stroke as well as the forward stroke; this may be provided for by employing a cam 316 pivoted at 317 in slot 308 above cam 306, and having an adjustable limit stop 318 extended downwardly to be acted on by plate spring 319, and adapted to be withdrawn during round and round knitting by a link 134 to the pattern devices, presently mentioned. If not withdrawn, this cam would needlessly stress the fabric at web-holders w^2 .

The tensioning effect of any of the web-holders w^2 being dependent upon whether it has been withdrawn abnormally, before reaching the cam 312, the invention includes means for acting on all or some only of these web-holders to predetermine abnormal withdrawal of selected members only or all of the series of web-holders w^2 . As shown, butts w^{17} , w^{18} of two different lengths only are sufficient for making the stocking of Fig. 24, the longer-butt web-holders being placed, see Figs. 22 and 23, to correspond to the instep p , and the shorter-butt web-holders being placed in the remainder of the circle; but any different arrangement of these web-holders and further differentiation of their butts may be resorted to for other purposes within the invention. To actuate these web-holders, a pattern-controlled withdrawing cam 325, Figs. 14, 15, 16 and 18, is the preferred instrument.

Having regard to the lack of space above the web-holder cap 300, the lost motion in a rotary sense of this cap, and the narrow space between the web-holder butts and the needles, I prefer to construct and operate the cam 325 as follows: An opening 326 is formed, see Figs. 16 and 18, through the upper surface of the web-holder-cam-cap 300 communicating with the groove 310. In this opening the cam 325 is arranged for vertical motion into and out of contact with the butts w^{18} and with the butts w^{17} of the web-holders w^2 , the lowermost position of the cam 325 being limited by the step 305 in the withdrawing cam 304.

The preferred means for mounting and operating the cam 325 comprises an arcuate segment 327 of spring metal (see Figs. 14 and 15) extending around substantially half of the upper surface of the cam cap 300 to which it is attached by screws 328, 328. This spring segment 327 is bent upwardly from points near the screws 328 to provide a

flat portion 329 normally raised above the upper surface of the cap 300 and having cam 325 mounted on its under side by the screws 330. The flat portion 329 of the 5 spring 327 is provided with an outwardly extending lug 331 of greater angular extent than the usual lost motion movement of the cap 300.

Any suitable means for depressing the 10 cam 325 automatically may be provided; for instance, referring now to Figs. 1 and 20, one of the thrust bars 460 comprising the pattern operated connections from the drum 120 is provided with an adjustable actuator 15 332 having an inward projection resting above the lug 331. Downward movement of the thrust bar 460 by its relatively heavy spring 333 will depress the spring 327 and the cam 325 to the extent determined by the 20 operating cam (such as 325^a, Fig. 13) for that bar 460 on the drum 120. This cam may, according to the product, have a portion *e* corresponding in height to the idle 25 position, a portion *e'* to the partly depressed position, and a portion *e''* to the fully depressed position of cam 325, and corresponding in angular extent to the length of the plain, the partly-ribbed-and-partly-plain, and the all-around-ribbed parts of the fabric, respectively.

Whenever the actuator 332 is elevated to the position shown in Figs. 1 and 20, for instance, the cam 325 is withdrawn by the spring 327, and all of the web-holders are 30 normally actuated. Whenever the cam 325 is depressed through a part of its useful freedom of motion, it first contacts with the leading high butt *w*¹⁸ of the series of web-holders *w*² and then abnormally withdraws 35 each of the high butt web-holders *w*². When resting against the step 305, at its lowest position, the cam 325 acts upon and withdraws all of the web-holders *w*². The stages of motion downward of cam 325 are 40 timed, by the usual devices for moving drum 120, to take place just prior to passage of the leading long butt and the leading short butt dial needle. The cap 300 may be cut away at 324, Figs. 15 and 16, to 45 permit the abnormal outward movement of the web-holders.

Means for giving related motions to the cylinder and dial and the web holders may be provided as follows:

50 Referring now to Figs. 1, 2, 20 and 21, vertical motions of the dial may be secured by any convenient automatic connection under control of pattern surfaces of the machine, such as a cam on or rotating in unison with the main cam shaft 80. A preferred connection for this purpose comprises an appropriate cam 80^a, Fig. 20, attached to the face of the gear 122 on the end of the shaft 80 and an appropriate lever

122^b worked by this cam, having a vertical 65 operating connection 125.

The connection 125 passes up behind the drum 120 to a link 126 pivoted to the connection 125 and to the latch ring pivot post 401. The upper end of the connection 125 is 70 provided with an adjustable piece 127 taking under a lever 128 pivoted at 129 in the fore-and-aft slot 130, see Fig. 2, formed in the gear-casing B' forming a part of the bracket A attached to the latch ring 550. 75 The lever 128 thus stands between the upward extension of the dial spindle *d* and the gear *g*² forming a part of its driving train. The dial spindle is splined at *g*¹ to slide through and rotate with the gear *g*¹, and is 80 provided with an arm *d*¹³ held to a bearing upon the upper end of the dial spindle *d* by a cap *d*¹⁴ fastened through a bore in the arm *d*¹³ to the dial spindle *d*. The arm *d*¹³ carries a downwardly extending adjustment 85 screw *d*¹⁶ lying above the lever 128, and is also provided with a steady connection *d*¹⁰ extending through a hole in bracket A to the dial cap D' presently mentioned. These arrangements are such that up and down motion of the rear end of the lever 128 will move the dial (and the dial cap resting upon its upper face) vertically through the desired small distances, in time with the rotary 90 motions of shaft 80 and the gear 122. The vertical motions of the cylinder 260, controlled through the lever 281 and the drum 120, are thus coordinated with the means for vertically positioning the dial.

Cam 80^a may have as shown high parts 80^b, 80^c, 80^d respectively corresponding to high positions of the dial for the plain-fabric knitting at the selvage, looper's rounds, the toe, the toe part of the foot; at the heel; and at the welt. The intervening low parts 80^e, 80^f, 80^g respectively position the dial in a low position for the partly ribbed and partly plain tube for the instep and sole; for the partly ribbed and partly plain ankle section, the ankle and leg; and for the 105 ribbed fabric following the welt.

In some cases, as when it is desirable to change yarns during the leg to compensate for the increased stitch-length and higher 110 positions of the needle cylinder caused to fashion the calf of the leg, and for other purposes, the dial may be lifted to better accommodate the thicker fabric made by the heavier yarn, the higher position of the needle cylinder and web-holders. Segment 115 80^h of the cam 80^a may have a higher place 80^h, Fig. 21, for this purpose.

The connection 125 also works the bell-crank lever 133 to operate the link 134 for moving a cam 316 on the web-holder cam cap, Figs. 15 and 16, to advance the web-holders for reciprocal heel and toe knitting. This arrangement is such as to en-

able the dial to be positioned as desired by motions of connections 125 through an upper range of its movements; and to enable the connection 134 to be pulled upon to withdraw cam 316 when the dial is in its low position for rib knitting.

Dial needle motions.—For rib knitting, when the dial needles are operative as secondary needles, as preferred, to knit in the 10 radial plane y , Figs. 5 and 6, following, in the rotation of the machine, the radial plane k at which the cylinder needles knit, the dial needles are supplied with yarn by the runs of yarn lying between the hooks of the 15 cylinder needles, and the rib or back wales x^1, x^2, x^3 , etc.; Figs. 23 and 27, knit by the dial needles, are formed of these runs of yarn.

Preferred means for giving the dial needles their motions will be understood by reference to Figs. 2, 6 and 7. The dial cam cap D^1 , held against rotation by the post d^{10} , carries cam rings d^{16} defining between them a broad concentric groove d^7 . Mov- 25 able knitting cams are interposed in this groove, and certain fixed cam margins of this groove cooperate with the interposed cams.

The movable knitting cams may comprise 30 the cam 13, for advancing the hook parts a of the needles, the cam 12 for advancing the point parts b of the needles, and the cam 10, which operates on both the hook member a and the point-member b of the dial needles. 35 The dial cams may also include a fixed separator cam 14.

When the respective butts of the part a of the needle and the part b travel concentrically in the broad groove d^7 , the dial needles 40 are in their idle or welting position illustrated in Fig. 2.

Preparatory to receiving new yarn, both needle members are advanced, respectively by the cams 12 and 13, and the last previous 45 dial loop, the fabric being restrained from following by the web-holders, will have slipped up upon the shank of the hook member a , and thus will be in position to be entered from without and lifted by the point b^{10} of the member b . The member b is now retracted for the purpose of taking this loop on the point b^{10} . This movement is effected by the fixed withdrawing incline 15. The hook a^{10} of the part a of the needle is now 50 exposed to receive yarn, which is accomplished by the descent of the cylinder needles with the new yarn in their hooks.

This secondary feeding takes place be- 55 tween the planes y^3 and k , Fig. 5, so that the needle part a upon further recession, draws the dial loop subsequently to knocking-over of the cylinder loop, and during rise of the cylinder needles between k and y . The inward motion of the needle part a is completed at the apex of cam 10 (at

plane y) during that position of the rising cylinder needle which most relaxes draft upon the course of yarn and during tension on the fabric due to web-holders w^2 and w^1 , which have now been reinserted. The 70 tension on the fabric by the tensioning web-holders w^2 is transmitted from their relatively remote serrated ends, is measured by the spring pressure at cam 312, and is exerted in the wales corresponding to the dial 75 needles.

The recession of the dial needles to the point indicated in Fig. 2, just within the dial verge d^2 , would not be sufficient to cast off the previous loop if the dial needles were 80 any of the kinds of needles customarily employed. But outward motion of the points b^{10} aided by the tension on the fabric of the tensioning web-holders w^2 , now lifts the loops off the needle parts a , the advance of 85 the point member b releasing the loops and dropping them on to the new loops.

This loop-lifting and cast-off movement of the members b is effected by the overthrow 90 surface 11 of cam 10 (Fig. 6).

The dial needle parts a and b are now 95 returned to their idle position by the cam slopes 10^a and 10^b respectively (Fig. 6).

The cams 10, 12 and 13 of the knitting cam group are suitably, and by preference 100 adjustably, mounted together for motion on dial D^1 toward and from the needles; for instance on a carrier block 615, Fig. 7, having holes guided on vertical pins 616 and 618 on dial cap D^1 , and also having a housing 617 over pin 618 for a spring taking 105 against the top of pin 618. The dial cap is cut through at d^{30} to permit the cams carried by the block 615 to enter into contact with the needle butts, whenever the housing 617 is pushed down by the inner end of a lever 613, pivoted at 612 to a bracket 620 attached, for instance, to the latch ring 550.

The lever 613 is operated by suitable cams such as 120^a, Fig. 21, on drum 120, and the thrust bar 461, the upper end of which takes 110 against a pin 529 eccentrically mounted for adjustment at the outer end of the lever 613 (Figs. 1 and 7).

When block 615 is depressed only so far 115 as to engage its cams with the longer butt series of the needles a b , the dial needles are entered and operated in a corresponding segment only of the fabric.

When further depressed, all of the dial 120 needles are operated. When withdrawn after knitting, all of the dial needles are left in the position of Fig. 2, and the dial loops are retained for welting or other purposes.

When, as explained above, it is desirable to lift the dial during rib knitting, for example by the segment 80^b of cam 80^a, Fig. 21, the inward end of lever 613 is prefer- 125 ably lifted to avoid motion of the dial knit- 130

ting cams in respect to dial cap D', which rises with the dial. This is provided for by providing a step 120^y in cam 120^x for the bar 462 to a lower level conforming in angular position to the effective position of the segment 80^h on cam 80^a.

Yarn feed means.—The machine is provided with usual yarn-feeding means for a stocking knitting machine, including a series of pattern-controlled yarn feed guide fingers F' adapted to be lowered into operative position as shown at the left of the series in Fig. 7, and raised to inoperative position. One or more of these yarn guides may be arranged to be actuated for splicing or other auxiliary yarn supply, and any of them may be worked for yarn changing by the usual expedients. Except when splicing, the yarn withdrawn from knitting is thrown above the upper surface of the dial cap D', upon which it is taken under the clamp member c and is severed by the shears c', the clamp and severing means being appropriately operated by the lever 611 and one of the thrust bars 460. In order to prevent the withdrawn yarns from passing above the cam carrier block 615, the preferred structure includes a spur 615^a projecting radially from the block 615.

30 The usual brush latch-opener 425, Fig. 5, is preferably employed, and the machine may be driven through automatic speed-changing power connections.

Cylinder-needle operating devices.—Referring to Figs. 24 to 27 and Fig. 5, the selvage s by which the fabric is begun on the bare needles, the last stocking having been cast off, may be made according to my said reissued Patent No. 13,752 by feeding an initial yarn from one of the yarn-fingers F' first to ever-active recurrent cylinder needles only, the remainder being inactive, and then normally actuating and feeding all of the cylinder needles. For this purpose the dividing cam 4, Fig. 5, is caused to enter in two stages, depressing in turn below the leading stitch cam 360 all of the long and short butt series of needles not provided with jacks 380. Jacks 380 operate at cam 366 to lift their ever-active needles back to the normal path above cam 360. The depressed needles without jacks travel below the normal (dotted-line) position of lower center cam 9 and rejoin the other needles under cam 361. Cam 4 is then withdrawn to run off the end of the long butt series (with which the medium butt needles n² are included). If the yarn finger F' entered its yarn just before the last long butt needle passed it, the cam 4 being in, the yarn will now have been fed to all of the needles with jacks, and will be held inward at the places of the intervening needles by the action of the web-holders. On the next course, cam 4 being withdrawn, all of the needles knit, thus forming the sel-

vage s, and subsequent fabric may be made as desired. Cam 4, see Figs. 1 and 5, may be, like similar cams of my prior patents, the inner end of a slide, worked by a horizontal lever 24 from a cam 23 on a thrust-bar 461 moved by cams on drum 120 in proper time with passage by it of certain segments of the needles.

I utilize the devices referred to combined with other devices, for the purpose of making the eyelet-hole-closing and ribbed-fabric demarking courses r¹ and r², Figs. 24 and 27, by a tucking operation.

The lower center cam 9 which is commonly fixed, is in this case pivoted at 7 (Figs. 5, 12 and 13) and is provided with a pin 9^a extending through a hole in the cam cylinder 271 to engage the forked inner end of an actuator 20 adjustably fastened by screws 22 to a thrust bar 460. When bar 460 is lowered, cam 9 is positioned, as shown in Fig. 5, across the path of needle butts depressed by cam 4 to pass under cam 360, and these needles, which have not cleared their previous loops, pass up cam 9 to take yarn, in addition to their previous loop, from any finger F' which may be in operative position. Although those needles then travel down cam 361, they do not knit, not having cleared. But on the next course, if not again depressed by cam 4, the old loop r⁶ and the bight r⁷ (Fig. 27) of yarn so received are both cast off on the yarn loop normally taken in course r⁵.

Cam 9, when tilted as shown in Fig. 5, 100 functions normally for needles passing over cam 360 and under cam 357 in round and round knitting, and need be in its normal position only when needles depressed by cam 4 must pass the yarn feed guides without taking yarn, e. g., for the selvage s, and during heel and toe knitting. A suitable cam 21 on drum 120, Fig. 13, lifts the bar 460 to restore cam 9 to its normal position after the special function is performed. Cam 4 105 is operated to cause the jackless needles to tuck during so many courses or such parts of courses as it is effective to depress these needles. The preferred structure detains the loops r⁶ during one subsequent course only. 110

Normal operation of the cam 4 to produce a single course containing the tuck stitches such as the courses r⁸, r⁹ of Fig. 27 will therefore be occasioned by a motion of drum 120, acting through the thrust bar 461 and the cam 23 to insert the cam 4 to first operate the longer butt needles, to then operate the shorter butt segment of needles and to run off the last needle of the long butt segment on its second passage. In order to 120 confine the combined effect of the cams 4 and 9 to a single course or to a segment only of a single course the cam 25 is arranged for co-action with the needles to advance the leading longer butt needle and those following 125 130

above the reach of the cam 4. For instance, if the cam 25 is inserted after entrance of cam 4 during the passage of the short butt needles, the cam 4 being active, the effect of the cam 4 would be confined to the long butt needles previously actuated and the short butt needles, and cam 4 can thereafter be withdrawn out of reach of the short butts at any time after a single whole revolution.

10 But if it is desired to tuck only on some segment of the needles selected by their butts, for example to tuck on the long butt needles n^1 only, this can be accomplished in the following way:

15 The inward motion of the cam 4 is confined by a suitable operating cam on the drum 120 to contact with the longer butt segment of needles n^1 only. The combined effect of the cams 4 and 9 is now only upon 20 the segment of needles n^1 , corresponding to the dial needles having the longer butts a^1 and b^1 . Motion inward of the cam 4 to this extent may therefore be employed to make the demarking structure r^1 at the beginning 25 of the ribbed fabric for the instep of the stocking.

When it is desired to knit the demarking structure n^2 on the complementary segment of needles, for instance on the short butt needles 30 n^2 and the intermediate butt needles n^3 , this is accomplished by the combined action of the cams 25 and 4, these cams being positioned together inwardly so that the cam 25 encounters the longer butts and raises them 35 out of the reach of the cam 4, which, during their passage, is positioned all the way in to encounter the medium and shorter butt needles, and cause those among them without the jacks 380 to pass up the cam 9 and 40 take the yarn without having cleared. It will be apparent that the selection of any series of needles having differentiated butts, e. g. of the medium butt needles n^3 , is easily 45 accomplished by this combination of devices.

In order to coordinate the motions of the cam 25 with the motions of the cam 4, and referring now to Figs. 1 and 12, I prefer to 50 operate the cam 25 from the primary pattern chain C rather than from the main pattern drum 120. For the specific purpose of making the product illustrated in Figs. 24 and 27, activity of the cam 25 follows shortly after the knitting of heels and toes, and for 55 this and other reasons it is convenient to operate the cam 25, the switch cam 415, and the widening picker 680 (all active at about this general time), from the same connections, which can have different positions for 60 these respective purposes.

Referring to Fig. 1, on the stud shaft 200 a rocker 201 having an arm 202 standing over the position of lugs 203 on the left hand side of the mutable-link pattern chain C is 65 provided with forked arm 204 taking under

a collar 205 on an actuating thrust rod 206. This rod passes upward through a hole in the bed plate B and is provided with a collar 207 having a finger 208, Fig. 12, bearing eccentrically on an arm 208^a of the short shaft 70 209 on which the picker 680 is pivoted, and forming part of its universal motion mounting. Upon depression of the shaft 206 the picker 680 is made active in the usual way for the usual stocking knitting purposes. 75 The lower end of the thrust rod 206 is pivoted at 210 (Fig. 1) to a lever 211 pivoted at 124 and having one end in contact with cams on the drum 120; this part of the described connections may be relied upon to 80 drop the rod 206 to actuate the picker controlling connections 207, 208, 209, at the proper time. This will be permitted by the absence of any lug 203 on the chain C which might retain the rocker 201 in its upward 85 position. The downward motion of the thrust bar 206 may be induced by cams on drum 120 (not shown) in two stages, for the purpose of operating the switch cam 415 during the first part of its descent and operating the picker 680 during the last part of its descent. As usual the switch cam 415 is mounted to rotate with a short shaft 416 having an arm 417 over the upper end of the rod 206. Shaft 416 is provided with a pin 418 in the cam slot 419, for the usual purposes. When heel and toe knitting is over the long butt instep needles which have been raised by the cam 415 are returned to their normal position by elevating the rod 206 by 90 the connection 210, 211 and 120.

For the purpose of operating the cam 25 the rocker 201, etc., is now relied upon to move the thrust bar 206 further upward, and this motion is transmitted to the cam 25 as 105 by a connection preferably comprising an arm 420 on the shaft 416, a horizontal rocker lever 421 pivoted at 422, Fig. 12, and taking under a depending pin 423 on an arm 424 pivoted at 42^a upon which arm the cam 25 110 is mounted. A spring 426 tends to keep the arm 424 inwardly against the rocker lever 421.

Upward motions of the thrust rod 206 by the rocker 201 and the lug 203 are permitted 115 by the connection 210, 211, which is merely lifted away from its normal actuating cams.

In order to insure that the needles travel on the ledge 41, for their accurate selection by the cams 4 and 25, or in order to adjust 120 the amount of yarn respectively in the cylinder and in the dial wale of the fabric, or in order to depress the needles to provide a place for the operation of a stop-motion detector, not shown, I prefer in some cases to 125 arrange for depression of all of the cylinder needles to a less extent than for knitting after both sets of needles have knit. The preferred means for this purpose is cam 8, Figs. 5 and 12, on arm 18^a pivoted at 18^b, 130

held inward by a spring 18^c, and moved outward by a rocker lever 18^d pivoted between its ends and operated by a connection 139 to a vertical operating lever 140, Fig. 1, which is pivoted on the stud shaft 450, and has its lower end on the path of cams of drum 120. The connection 139 is operated to remove the cam 8 during heel and toe knitting.

10 *Operation.*—In knitting stockings, the operation is from toe to top. Assuming the machine to be running and the needles to be bare of any yarn, the needle dial to be in its lowest position, and the yarn fingers F' to be elevated, their yarns being held under the clamp c and ready for reinsertion, the operation begins by the motion inward of cam 4 (Fig. 5) first to encounter the long butt needles, and then by a motion during their 15 passage to its inward position to move all of the needles. Cam 9 is in its normal upper position. The dial needles are retracted to their welt position, Fig. 2, the needles with the jacks 380 are taking their normal knitting path, and the needles without jacks are 20 passing below the cams 360, 9 and 361. A yarn finger F' is now dropped into operative position before and near the passage of the following end of the long butt needles, 25 and the cam 4 is moved outwardly to run off the end of the long butt series at its next passage, whereupon all of the needles will take yarn for a second course and subsequent courses. Enough fabric is thus knit on all 30 of the needles to provide the loopers' rounds r, Fig. 25.

A motion of the drum 120 now operates the lever 281 to make a loose course by raising the needle cylinder and web holders during one revolution, and the further motion of the pattern shaft 80 shifts the actuating elements of the machine to reciprocal motion, lowers the cam 415 to switch the long 40 butt and medium butt needles above the stitch cams, and the machine knits the toe pocket t as usual, the narrowing pickers 650 diminishing the series of active needles. A short motion of the drum 120 now puts the widening pickers 680 into action, and a further motion of the shaft 80 causes the machine to resume rotation, the switch cam 415 to be lifted to switch down the long and medium butt needles, and a change of yarn 45 to be effected if desired. The machine now knits the usual ring of fabric t' following the toe for a few rounds.

The next motion of the pattern mechanism drops the lower center cam 9, inserts cam 8, and inserts the cam 4 to position to act on the long butt needles only, whereupon the demarking structure r¹ is made on the long butt segment of cylinder needles, and cam 4 is removed.

50 Dial D now descends to its lower position. The cam block 615 is moved down to engage

the knitting cams with the longer butt series of dial needles only. These needles enter into course r⁵ in Fig. 27 and each of them takes an initial loop z, and the instep p and sole S is knit with the parts in this adjustment.

During the preceding operations the web-holder-withdrawing cam 325 (Figs. 14 to 18) has been in its upper idle position, and all of the web holders have been normally actuated. This cam 325 is now moved downward by its operating connection to abnormally withdraw only those web holders w² having the longer butts w¹⁸. On the completion of enough partly ribbed and partly plain fabric for the foot, the knitting motion is changed to reciprocation, the switch cam 415 is lowered and simultaneously the dial needles are retired by motion upward of the block 615, with the effect of retaining the dial loops; the web holder cam 325 is lifted out of action, the dial is raised coordinate with the upward motion of the instep segment of cylinder needles at cam 415, and the heel is then knit as usual in making plain fabric stocking.

At the end of the heel the dial is lowered, the cam 325 is again placed in position to act on the high butts w¹⁸ of the web holders w², and the dial cams are rendered active by again depressing the block 615 coincidently with resumption of rotary motion of the needle cylinder and dial. In this condition the machine is operated to make the section of plain fabric h' above the heel and to continue ribbing at the instep segment.

It will be observed that the instep section p of the fabric may be as much less than half of the circumference of the tube knit as desired, the medium butt needles n³ occupying spaces intervening between the ends of the short butt heel and toe knitting needles and the position of the ribbing needles. This provision enables the foot p, S, to be made narrow, the added rib wales being comparatively few in number, and their tendency to increase the width of the fabric being compensated for by the relatively larger segment of plain fabric knit on the short butt and medium butt needles, and of course, with a short stitch as governed by the vertical position of the needle cylinder at this time.

The machine is now ready to begin knitting rib fabric all around the leg, and for this purpose the cam 25 is moved in to lift the long butt needles over the dividing cam 4; cam 4 is moved in and cam 9 positioned to carry down and tuck on the medium and short butt needles, and for the next course cams 25, 4 and 9 are taken out of the way, to knit on all the cylinder needles; the dial cams carried by block 615 and the web holder cam 325 are moved downwardly to their extreme position, respectively to op-

erate all of the dial needles and to properly tension the ribbed fabric all around the tube.

Knitting now proceeds with a short stitch for the ankle, with a gradually increasing 5 stitch for the calf of the leg, and if desired with a change or changes to heavier yarns, as explained above. When sufficient fabric has been knit for the upper part of the leg, the dial needle cams are then withdrawn upward to retire the dial needles to their 10 weling position while the cylinder needles continue to operate for about two courses; web holder cam 325 is retired; and the dial is then moved upward preferably in steps corresponding to intervals of one or two courses, 15 the growth of the welt fabric permitting this motion without strain.

When sufficient plain fabric W for the 20 welt has been knit the dial is again lowered, the dial needles are placed in action by lowering the block 615, the tensioning web 25 holders are placed in action and enough fabric, for instance from five to ten courses, is knit to form the rib fabric section W¹.

25 The completed stocking is now cast off by lifting out the yarn finger F' last in action, the yarn is clamped and cut, and the machine runs empty during several revolutions, the dial being slightly raised for a new 30 operation during this idle motion.

It will be observed that the described machine comprises means for knitting an article of hosiery partly of ribbed and partly of plain fabric, this article being characterized by a constant number of face wales throughout the fabric, those portions of the length containing ribbed fabric having an augmented number of wales, the additions being comprised of wales from one or more 35 segments of introduced dial needles, and further characterized by the presence in the article of hosiery of two or more places of introduction of the introduced back or rib wales. In other words, the machine includes 40 means for knitting an article of hosiery of a relatively constant number of wales made on continuously active needles (except as some of them may be differently employed for selvaging or tucking) and means for causing 45 to enter into rib knitting cooperation with the constant number of needles, first one and then another segment of ribbing needles. The means provided for the performance of 50 these functions thus permit plain fabric circular knitting, followed by circular knitting ribbed in one segment and plain in another segment, and in turn followed by circular fabric ribbed throughout the circumference of the tube; and these dispositions are such 55 as to permit the plain parts of the product to be provided with fashioned pockets for heel and toe, and such as to permit the automatic making and fastening down of a welt 60 following rib knitting. Concomitantly with 65 the provision of the above mentioned means,

and permitting the combination in an automatic machine of instrumentalities for these purposes, the invention provides a way of placing the ribbed fabric under appropriate tension for the kind of knitting, even when the production is a plain fabric on one side of the machine and a ribbed fabric on the other side.

What I claim is:

1. A knitting machine having therein a 75 series of needles and means cooperating with them to knit the face wales of an article of hosiery comprising a fabric of face wales augmented by accretions of back or ribbing wales, in combination with a second series of 80 needles and means for operating upon them to knit the back or ribbing wales, and with means for causing segments of the second series of needles severally to enter into operation, in succession, and with means cooperating with the entering segments of needles to maintain a different tension on the corresponding segment of the fabric from that maintained on the remainder of the fabric.

2. An automatic knitting machine of the 90 kind having two cooperating series of needles and means for knitting thereon tubular articles partly ribbed and partly plain, having therein means for producing articles in separate succession by knitting begun on the 95 bare needles by forming a selvage and ended by pressing off the fabric, in combination with means for beginning knitting on segments of said series of needles a ribbed fabric part of one circumferential segment of the article at a point a predetermined distance from said selvage and plain fabric for a complementary segment, in combination with means for causing an additional segment of one series of said needles to 100 cooperate with the other series after knitting a predetermined length of fabric, whereby to knit ribbed fabric for another segment of the article, and means for changing the 105 tension on the knit loops corresponding to the segments of ribbed fabric when knitting ribbed fabric begins.

3. An automatic stocking knitting machine of the kind having therein two cooperating series of needles and means for knitting thereon heels and toes, and having therein in combination means for beginning knitting ribbed fabric for one circumferential segment only of the stocking at a predetermined place, and pattern operated means for knitting ribbed fabric for another segment of the stocking at another predetermined place in the length of the stocking and in relation to said heels and toes and 110 with segmental series of tensioning web-holders and means for operating these in segments corresponding to the ribbed knitting.

4. An automatic stocking knitting machine having therein two cooperating series 115

5 of needles and means for knitting thereon heels and toes, means for knitting ribbed fabric for one circumferential segment of the stocking and plain fabric for a complementary segment beginning at a predetermined place, and means for knitting ribbed fabric for another circumferential segment of the stocking beginning at another predetermined place in the length of the stocking, 10 in combination with means for maintaining tensions on the fabric severally different for the ribbed and the plain portions.

15 5. An automatic stocking knitting machine having therein cylinder and dial needle carriers, means for rotating and oscillating said carriers, two cooperating series of needles respectively in said carriers and means for knitting thereon seamless tubular stockings partly ribbed and partly plain, 20 with heel and toe pockets in the plain fabric parts knit on one of said series of needles only, and having means for knitting the stockings in separate succession by knitting begun on the bare needles at the toe end of each stocking, and ended by pressing off the 25 fabric, in combination with means for introducing into coaction with the series of needles for knitting the plain fabric at predetermined places in the fabric first one and then another segment of the other series of 30 needles comprising needle operating cams for the dial needles movable into and out of contact with segments of said needles in a direction crosswise of the direction of operative motion of said needles.

35 6. An automatic stocking knitting machine of the kind having therein two cooperating series of needles and means for knitting thereon seamless tubular stockings partly ribbed and partly plain, with heel and toe pockets in the plain fabric parts knit on one of said series of needles only, and having therein in combination means for knitting the stockings in separate succession by knitting begun on the bare needles at the toe end of each stocking, and ended by pressing off the fabric, means for introducing into coaction with the series of needles for knitting the plain fabric at predetermined places in the fabric first one and then another segment of the other series of needles, and means for tensioning the forming fabric of the several segments differently during the operation of the introduced series of needles.

40 7. A knitting machine having therein needle carriers and series of needles respectively in said carriers capable of coaction for rib knitting, means to form a starting selvage on the bare needles, each series comprising segmental series of needles, in combination with means acting to operate a segment of one series of the needles for plain knitting and simultaneously to operate segments of both series for rib knitting, where-

45 by to knit a tubular fabric having ribbed and plain fabric side by side, means for knitting ribbed fabric in longitudinal continuation of the plain fabric, and means operating on the means for forming a starting 70 selvage for forming a demarking and eyelet-hole closing structure at the beginning of the ribbed fabric parts.

8. In a knitting machine, the combination of a series of needles and carriers therefor 75 with a series of web-holders, means for supporting and operating the web-holders for cooperation with the needles of one of said series, means for advancing and withdrawing the web-holders with respect to said 80 needles, and means for predetermined an abnormal withdrawing motion of a segment of the series of web-holders only for the purpose of tensioning fabric containing wales knit by a segment of the other series 85 of needles.

9. In a knitting machine, the combination of a series of needles and carriers therefor, a series of web-holders, recurrent members 90 of which are tensioning web-holders, means for supporting the web-holders, means for normally advancing and withdrawing the web-holders with respect to said needles, and means for predetermined an abnormal 95 withdrawing motion severally of different segments of said recurrent members of the series of web-holders in respect to the needles with which they are associated.

10. A knitting machine having therein, in combination, a series of needles, a series of plain web-holders, a series of tensioning web-holders intercalated among the plain web-holders, means differentiating one segment of the tensioning web-holders from another segment, and means for severally operating the series of plain web-holders and one or more segments of the tensioning web-holders severally to cause said segments respectively to tension or not to tension.

11. A knitting machine having therein, in combination, a series of needles, a series of plain web-holders, a series of tensioning web-holders intercalated among the plain web-holders, means differentiating one segment of the tensioning web-holders from another segment, a cam cap and cams thereon, 110 and means for operating the series of plain web-holders, and a movable cam on said cam cap for severally operating one or more segments of the tensioning web-holders.

12. In a knitting machine, the combination of series of needles and carriers therefor, web-holders, means for supporting and operating the web-holders for cooperation with the needles, means for advancing and withdrawing the web-holders with respect to said needles, and means for predetermined an abnormal withdrawing action of certain of the web-holders only in respect to the 125 needles with which they are associated com-

prising a cam movable into and out of co-operative relation severally with different segments of the web-holders.

13. In a knitting machine, the combination of a series of needles, a series of web-holders, means acting on all of the web-holders to advance them through a normal distance, and means for abnormally withdrawing and again advancing certain of said web-holders recurring in said series, in combination with means for confining the abnormal motion of withdrawal to one or more segments only of said recurrent members of said series.

14. A knitting machine having needles and web-holders in intercalated series differentiated from each other in three or more series, in combination with web-holder operating cams adapted to advance all of the web-holders, a web-holder cam adapted to withdraw all of the web-holders normally, means adapted to withdraw a different number of one class of the differentiated web-holders according to the adjustment of said means, and automatic devices for adjusting said means to control the operation of the web-holders.

15. In a knitting machine, a series of plain web-holders and a series of tensioning web-holders, the tensioning web-holders having operating butts some of which are different from the others, the plain web-holders having butts different from any of the tensioning web-holders, and means for operating the web-holders coacting severally with the different classes of operating butts.

16. In a knitting machine, a series of plain web-holders and a series of tensioning web-holders, the tensioning web-holders having operating butts some of which are different from the others, the plain web-holders having butts different from any of the tensioning web-holders, in combination with a web-holder cam-cap having cams constantly active on the plain web-holder butts and cams capable of adjustment to actuate or not to actuate one or more of the different kinds of butts of the tensioning web-holders.

17. In a knitting machine, a series of plain web-holders and a series of tensioning web-holders, the tensioning web-holders having operating butts some of which are different from the others, the plain web-holders having butts different from any of the tensioning web-holders, in combination with a web-holder cam-cap having cams adapted to advance to the same extent all of the web-holders, a cam for normally withdrawing all of the web-holders, and a cam movable on the cam cap for abnormally withdrawing the tensioning web-holders of one or more different kinds of operating butts, according to the adjustment of said movable cam.

18. In a web-holder mechanism for knit-

ting machines, the combination of web-holders having short broad butts, web-holders having longer and narrow butts, and web-holders having narrow and still longer butts with a cam-cap having a broad, shallow cam-groove and narrow, deep cam-groove, whereby the narrower butts may be given advancing and withdrawing movements within the width of the broad, shallow groove without necessitating similar movement of the broader butt web-holders.

19. In a web-holder mechanism for a knitting machine, the combination with a web-holder cam-cap having a withdrawing cam thereon of a movable cam for abnormal withdrawal of web-holders actuated thereby mounted on the cam-cap for motion at an angle to the direction of motion of said web-holders, and adapted to move the web-holders engaged thereby further outward than said withdrawing cam.

20. In a web-holder mechanism for a knitting machine, the combination with a web-holder cam-cap having a withdrawing cam thereon of a movable cam for abnormal withdrawal of web-holders actuated thereby mounted on the cam-cap for motion at an angle to the direction of motion of said web-holders, and adapted to move the web-holders engaged thereby further outward than said withdrawing cam, and a spring-pressed cam adapted to advance web-holders withdrawn by said withdrawal cams.

21. A knitting machine for making articles of hosiery partly of ribbed and partly of plain fabric, having therein series of needles and means for knitting upon them, in combination with web holders, means for causing each of said web holders to cooperate with the needles in use for making plain fabric, and means for causing certain web holders of a segment of said web holders only to engage the wales of previously knit courses of the ribbed fabric.

22. A web-holder cam-cap having thereon a cam on a spring mounting above and fixed to the cam-cap, and adapted to be inserted into and withdrawn from contact with the web-holders by depressing and releasing said spring mounting.

23. In a rib knitting machine, in combination with two series of coacting needles and their carriers, means for successively entering into action different segments of the needles of one of said carriers to begin making ribbed fabric thereat, and means for making a demarking structure in a preceding course of the fabric on corresponding segments only of the series of needles of the other carrier.

24. In a rib knitting machine, in combination with two series of coacting needles and their carriers, means for successively entering into action different segments of the needles of one of said carriers to begin mak-

- ing ribbed fabric thereat, and means for making tuck stitches on corresponding segments only of the series of needles of the other carrier.
- 5 25. In a knitting machine having yarn feeding means and needles having uniform latches requiring to be advanced and retracted respectively to clear their loops and to knit, knitting cams, and means for normally advancing certain recurrent needles at all times to clear their loops, in combination with means for causing a segment of the other needles to receive yarn without being advanced during one or more courses, and 10 means for causing like operation of another segment of said other needles in another course or courses.
26. In a knitting machine, yarn feed means, a cam cylinder, stitch cams for reciprocal knitting, uniform latch needles, means to cause recurrent needles to be advanced to clear their latches, needle dividing means adapted to be adjusted to cause certain of the other needles to pass under the leading 15 stitch cam, and a movable cam acting between said stitch cams for advancing said certain needles to take yarn to tuck, in one position, and permitting said needles to pass unmoved, in another position.
- 30 27. In a knitting machine, yarn feed means, a cam cylinder, stitch cams for reciprocal knitting, uniform latch needles, means to cause recurrent needles to be advanced to clear their latches, needle dividing means adapted to be adjusted to cause certain of the other needles to pass under the leading 20 stitch cam, in combination with a cam between the stitch-cams, and means for adjusting said cam to advance said certain needles to tuck by taking yarn uncleared or not to actuate them during an idle course or courses.
28. In a knitting machine, yarn feed means, a cam cylinder, stitch cams for reciprocal knitting, latch needles normally traveling between stitch cams at tuck position, means to cause recurrent needles to be advanced to clear their latches, needle dividing means adapted to be adjusted to cause 25 certain of the other needles to pass under the leading stitch cam, in combination with a cam between the stitch-cams and means for adjusting said cam to advance said certain needles or not to actuate them and pattern controlled means for severally positioning said needle dividing means and adjustable cam.
- 35 29. In a knitting machine, yarn feed means, a cam cylinder, stitch cams for reciprocal knitting, latch needles, means to cause recurrent needles to be advanced to clear their latches, dividing means ahead of the stitch cams adapted to be positioned to cause a segment of the needles having butts differentiated from the others to pass under the 30 stitch cams, and pattern-controlled means for advancing said needles out of reach of said dividing means.
30. In a knitting machine, yarn feed means, a cam cylinder, stitch cams for reciprocal knitting, latch needles, means to cause recurrent needles to be advanced to clear their latches, dividing means ahead of the stitch cams adapted to be positioned to cause a segment of the needles having butts differentiated from the others to pass under the 35 stitch cams, means for positioning said dividing means to act on all of the needles and pattern-controlled means for advancing said needles out of reach of said dividing means.
31. A stocking knitting machine having two series of needles for ribbed knitting, means for knitting heels and toes on one of said series including a segment of long-butts and a segment of short-butts needles, and means for predetermined rib-knitting and plain knitting in the instep and heel segments of parts of the stocking, in combination with means for making tuck stitches on recurrent needles respectively of the said 40 long-butts and short-butts segments in plain fabric courses preceding the knitting of ribbed fabric at said segments respectively.
32. In a machine for making partly ribbed and partly plain fabric, two series of needles, tucking means comprising in combination means for selecting certain needles among segmental groups of one of the two series of needles, and causing these needles to take yarn without casting off the previous 45 course, and pattern controlled devices for causing said selection and operation to occur in one or in another of said segmental groups.
33. In a knitting machine having a needle carrier, and needles, a stitch cam and yarn feed means, the combination of means for making a selvage by feeding yarn to recurrent needles and all the needles in succession including a dividing cam adapted to depress the intervening needles to pass beneath the stitch cam, with means for causing the needles so depressed to take yarn for the purpose of making tuck stitches.
34. In a machine for making partly ribbed and partly plain fabrics, a cylinder, a dial, needles therein, a series of fins on the dial in the planes of cylinder needles, and tensioning web-holders cooperating with the cylinder needles adapted to coact with the 50 fins in the planes of the dial needles for the purpose of tensioning the ribbed fabric.
35. In a machine for making partly ribbed and partly plain fabrics, a cylinder, a dial, needles therein, a series of fins on the dial in the planes of cylinder needles, and tensioning web-holders adapted to coact with the fins in the planes of the dial needles, in combination with means for raising and lowering the dial.

36. In a machine for making partly ribbed and partly plain fabrics, a cylinder, a dial, needles therein, a series of fins on the dial in the planes of cylinder needles, and tensioning web-holders adapted to coact with the fins in the planes of the dial needles, in combination with means for causing the tensioning web-holders to make normal and abnormal movements, and the dial needles to be active and inactive respectively.

37. In a rib knitting machine a cylinder and dial, two-part needles in the dial, said parts each having in one segment of the series needle butts of different length from those in another segment, in combination with means for actuating the needle parts adapted to be positioned to act on the butts of one kind only, the butts of all kinds, or to be inactive.

38. In a knitting machine having a needle carrier and needles, a stitch cam, heel and toe mechanism including a switch cam and pickers, and having needle selecting devices, means for controlling at different times in the operation of knitting a stocking the switch cam and pickers and the needle select-

ing devices, comprising a single common connection adapted to operate these parts severally when moved to different positions, a pattern mechanism comprising a primary pattern surface, a main pattern surface moved at times by means controlled by said primary pattern surface, a connection from the main pattern to said common connection for moving said common connection at times to one position, and means coacting directly with said primary pattern surface for moving said common connection at other times to another of its operative positions independently of said main pattern surface.

39. In a rib knitting machine having a dial and dial cam cap adapted to be vertically adjusted in accordance with changes of thickness and other changes in the fabric, an adjustable cam movable vertically on said cam cap, an operating connection to a relatively fixed part of the machine, and pattern means for moving said connection to compensate for different elevations of the dial.

Signed by me at New York city, New York, this fifth day of May, 1922.

ROBERT W. SCOTT.
